MESSAGE SHEET

William P. Rend, Chicago, Ill.

Application September 1, 1943, Serial No. 500,784

3 Claims. (Cl. 229—92.1)

1

My invention relates to message sheets adapted to be folded and secured together for mailing.

The principal object of the invention is the provision of an improved message sheet adapted to be folded to form an envelope.

A further object is the provision of such a message sheet of very simple design adapted to be readily folded to envelope form and as readily unsealed without the necessity of extensive instructions and in such a way that even the person unacquainted therewith is not apt to make a mistake.

A further object is the provision of such a message sheet adapted to be provided in the form of single sheets or capable of being clipped together in the form of a tablet or part of a bound series of forms such as of an order blank, invoice or the like.

Other objects and features of the invention will be apparent from a consideration of the following detailed description taken with the accompanying drawing wherein—

Fig. 1 is a plan view of a form comprising a preferred embodiment of my invention;

Figs. 2, 3 and 4 show successive steps in the folding of the form to produce an envelope;

Fig. 5 shows the completed envelope with provision for address and stamp;

Fig. 6 shows the manner of opening the form or "unsealing" the envelope; and

Fig. 7 shows the message sheet unfolded after the seal of the envelope has been properly broken.

Referring now to the drawing, the principal parts of the form of my invention are a message sheet 10, with bottom extension 11, top extension 12, and closure flap 13. Lines of perforations 14 and 16, respectively, separate the bottom and top extensions. It will be noted that the closure flap 13 occupies a central position. Preferably, it is gummed for quick sealing in a manner to be described.

Sides of the message sheet are foldable along broken lines 17 and 18 in the manner shown in Fig. 2 as the first step in the folding of the form, the portion of the top and bottom extensions being folded in with the side portions of the rectangular message sheet. The entire form is then folded along the broken line 19 to the position shown in Fig. 3, thus enclosing the folded-over portions resulting from the first folding to the position shown in Fig. 2. In this position, the lines of perforations 14 and 16 are aligned with each other. The closure flap 13 is then folded over to the position shown in Fig. 4 and sealed to complete the envelope.

2

The form is preferably printed with instructions and other indicia to facilitate folding to proper final finished envelope position. Indicative of the instructions are those appearing on the top and bottom extensions, it being noted that all of the instructions with respect to folding appear on the extensions. As indicated in Figs. 3 and 4, instructions with respect to opening appear on the main message sheet but, if desired, they may also appear upon the back of flap 13.

As to the folding in of the sides, it will be noted that in line with the broken lines 17 and 18, at top and bottom, there are printed lines indicating the line where the fold is preferably made. Fig. 2 indicates that the form is slightly scored as if by folding along the broken lines 17 and 18. The form may be so finished when produced, if desired, but, generally speaking, it is adequate merely to indicate the point where the fold occurs by the use of printed lines on the top and bottom extensions, leaving the entire message sheet itself free for such message as one will wish it to contain. The same is true of the line between the closure flap 13 and the top extension 12, preferably the line separating the closure flap 13 and the top extension 12 is not perforated; it is, at most, scored to facilitate folding.

The message sheet 10 is rectangular and may be standard letter size, if desired. Preferably, the fold, such as along the broken lines 17 and 18, is such as to bring the side edges practically in contact with each other as illustrated in Fig. 2. There may, of course, be an overlapping or some space left between the edges but this is not so desirable and does not result in the production of a flat but sturdy and strong envelope. The closure flap 13 may be relatively narrow (that is, looking at the direction transversely of the form itself) but preferably has its ends coinciding with the lines such as 17 and 18 along which the form is initially folded so that when folded over as in Figs. 4, 5 and 6, the closure will seal the entire end of the closed form and there will be no point at which a single unfolded edge of the form will be exposed. This means when the edges are brought together as in Fig. 2 that the closure flap 13 is not longer than half the width of the letter sheet but preferably at least almost half of such width.

The message form of my invention is simple and lends itself to the use of all modern systems for preparing, handling, stamping, addressing, and otherwise treating letters, invoices, forms, envelopes and the like. When I refer to "mes-

sage" I mean to include any intelligence that may be conveyed from one person to another whether that be a longhand letter, a typewritten letter, a form or mimeograph letter, an invoice, statement, bill, advertising circular, or the like.

Figs. 5 and 6 indicate that the back of the message sheet has been appropriately printed to show lines for an address and that the letter has been addressed longhand. Those skilled in the art will understand that this is merely illustrative. The back of the message sheet may be entirely unprinted, the name and address being applied by typing, by printing, by the use of an addressograph, or the like. The great advantage of the form comprising my invention is that it is so very simple that, generally, instructions for opening need not be given and, if desired, the back portion may be entirely unprinted.

I have referred to the fact that the form of my invention may comprise a single sheet or that it may be bound with other sheets as part of a series of forms such as used for order blanks, invoices, and the like. In such event, it is not essential that all of the sheets of the group of forms be finished for mailing. The forms may, of course, be tabbed for binding along any one of the four edges and if it is desired that the binding and the tabbing be at the top then the closure flap 13 may as well be placed at the bottom without departure from the essential features of the invention.

I am aware that other forms of alleged combination letters and envelopes have been produced in the past but I have found none which offers the advantages of simplicity, versatility and saving of paper and time as does the form of my invention. I do not wish to limit myself to the exact form of the invention disclosed. I have defined the scope of my invention in the appended claims.

What I claim as new and desire to protect by Letters Patent of the United States is:

1. A message form comprising a rectangular message sheet, narrow top and bottom extensions, each connected to the message sheet by a line of perforations, and a sealing flap projecting upwardly from a center portion of the said top message sheet extension, said sealing flap occupying approximately half of, but not more than half of, the width of the message form, said message form being folded along parallel vertical lines to lay side portions above a center portion with side edges contiguous to each other along a center line of the message form, and the message form so folded being again folded on a transverse line to align the said top and bottom lines of perforations and envelope said side edges, said

sealing flap being foldable for sealing to a contiguous back portion of said bottom message form extension, the message form after sealing being opened by a single tearing motion along the lines of perforations to separate the top and bottom extension from the message sheet.

2. A message form comprising a rectangular message sheet, narrow top and bottom extensions, each connected to the message sheet by a line of perforations, and a sealing flap projecting upwardly from a center portion of the said top message sheet extension, said sealing flap occupying approximately half of, but not more than half of, the width of the message form, said message form being folded along parallel vertical lines to lay side portions above a center portion with side edges contiguous to each other along a center line of the message form, and the message form so folded being again folded on a transverse line to align the said top and bottom lines of perforations and envelope said side edges, said sealing flap being foldable for sealing to a contiguous back portion of said bottom message form extension, the message form after sealing being opened by a single tearing motion along the lines of perforations to separate the top and bottom extension from the message sheet, the front face of the said top extension bearing instructions with respect to using and sealing the message form, and the back face of said top extension bearing instructions with respect to opening the message form.

3. A message form adapted to be folded to produce its own envelope, said message form comprising a rectangular message sheet, top and bottom extensions connected to the said rectangular message sheet by lines of perforations, and a single piece gummed sealing flap extending from only one of said extensions substantially at a mid-portion thereof, said form being folded in a manner such that side portions of said message sheet and including said extensions are folded over and toward each other, the whole then folded along a transverse center line to enclose said previously folded over portions and the gummed flap then folded and secured to a contiguous portion of one of said extensions, the said lines of perforations then being aligned, so that the form may be opened by tearing along such perforations and leaving a rectangular message surface, said gummed sealing flap occupying about one-half of the lineal dimension of the extension to which it is attached, and the sides of the rectangular letter form being adapted to fold in so that the side edges of the message form lie substantially along a longitudinal center line.

WILLIAM P. REND.
